UNITED STATES PATENT OFFICE.

HENRY G. REIST, OF LYNN, ASSIGNOR TO THE GENERAL ELECTRIC COMPANY,
OF BOSTON, MASSACHUSETTS.

COMMUTATOR-BRUSH.

SPECIFICATION forming part of Letters Patent No. 501,960, dated July 25, 1893.

Application filed March 15, 1893. Serial No. 466,086. (No model.)

To all whom it may concern:

Be it known that I, HENRY G. REIST, a citizen of the United States, residing at Lynn, in the county of Essex and State of Massachusetts, have invented certain new and useful Improvements in Commutator-Brushes, of which the following is a specification.

My invention relates to commutator or current collecting brushes for dynamo electric machines and has for its object to provide a brush of great carrying capacity and relatively high specific resistance, whereby a large current may be carried to translating devices of any kind while the sparking due to short-circuiting segments of the commutator is reduced to a minimum. The construction I adopt to attain these ends is more fully described hereinafter.

In order to attain a high specific resistance, carbon brushes have been used, and have been found desirable; but the current carrying capacity of such brushes is extremely small, and it has not been found advisable to use them with currents of low potential, less than one hundred volts or thereabout. They are not therefore adapted to dynamos giving large current of low potential or to motors, as they require a large commutator and a multiplicity of brushes in such case. It is to avoid the faults in such brushes that I have devised my present invention.

In the drawing hereto annexed and hereby made a part of this specification I show in perspective a representation of a brush embodying my invention.

A represents such a brush composed as shown of several laminæ of German silver or other conducting material, B B. These laminæ are fastened together at their back ends by rivets or solder, thus making good electric connection with one another. At the top and bottom I put backing plates, as D D, for the purpose of giving increased stiffness to the brush.

As thus constructed the brush would be similar to those in common use and open to all their objections; but in order to increase the specific resistance of the brushes I cut transverse slits E E in the laminæ B extend-

ing a greater or less distance across each one 50 of them, and by this means I attain the objects desired. The brush thus constructed may be secured to any suitable brush holder and may be slid forward or back between the plates D D, to adjust its position with reference to the commutator C, in the usual manner. The slits E E are to be punched so as to adjust the resistance of the brush to the potential of the current it is to carry, or to the difference of potential between the commutator segments.

In some cases I prefer to arrange the slits in the laminæ B B at other than a right angle to their length, as in the wear of the brush this does not make a sudden change in its 65 current-carrying capacity when it reaches the slit; the slit is thus presented diagonally to the commutator, and the brush wears gradually away from one side to the other. This construction is shown by dotted lines in the 70 drawing.

It is manifest further that electrical connection between the laminæ may be made by their contact merely; and they may therefore be loosely assembled and then brought 75 into closer contact by a clamp or by the brush holder, if so desired.

It is preferable to have an insulating film between the sheets or metal laminæ such as a coating of insulating scale, varnish, or thin 80 paper interposed, or the like, extending between the sheets or laminæ except where they are fastened together or united at the outer part of the brush.

Having thus described my invention, what 85 I claim, and wish to protect by Letters Patent of the United States, is—

1. A commutator brush composed of laminæ having transverse slits, substantially as described.

2. A commutator brush composed of superposed laminæ as B B having transverse slits as E E, the laminæ inclosed between backing plates as D D, substantially as described.

3. A commutator brush composed of laminæ B B connected together at their rear ends and inclosed between backing plates as D D, the laminæ having transverse slits as E E,

whereby the specific resistance of the brush is increased.

4. A commutator brush composed of laminæ as B B having transverse slits as E E, and inclosed and movable back and forth between backing plates as D D.

5. As articles of manufacture, laminæ for commutator brushes composed of metallic

strips whose continuity is interrupted by transverse slits, substantially as described. 10

In witness whereof I have hereunto set my hand this 13th day of March, 1893.

HENRY G. REIST.
